(57) **CLAIM**

The ornamental design for a urinary capture device, as shown and described herein.

DESCRIPTION

FIG. 1 is a top, perspective view of the urinary capture device comprising my new design;

FIG. 2 is a bottom, perspective view of the design of FIG. 1;

FIG. 3 is a top view of the design of FIG. 1;

FIG. 4 is a bottom view of the design of FIG. 1;

FIG. 5 is a left side elevational view of the design of FIG. 1, wherein the right side elevational view is a mirror image thereof;

FIG. 6 is a front elevational view of the design of FIG. 1; and,

FIG. 7 is a back elevational view of the design of FIG. 1. The broken lines shown in the figures are directed to the environment and are for illustrative purposes only; the broken lines form no part of the claimed urinary capture device invention.

The relatively light uneven broken lines shown in the figures represent contour, not surface decoration.
